CONVECTOR FOR GAS HEATERS

Augustus A. Straub, Cleveland, Ohio, assignor
to A. A. Straub Company, Inc., a corporation
of Ohio

Application October 14, 1948, Serial No. 54,543

6 Claims. (Cl. 263—47)

1

The present invention relates generally to convection space plates and more particularly is concerned with a novel and very economical and useful annealing tray.

In the batch annealing of coils of metal in strip, rod or wire form, it is customary to arrange the coils in stacks with spaces between adjacent coils so that heated gas may flow transversely of the coils and transmit heat rather ineffectively by conduction and convection to intermediate portions of the metal stock as well as to the outer portions thereof. Space plates or trays are the conventional spacing means for this purpose, being sandwiched between adjacent coils. Because of the considerable weight of the individual coils and the multiplication of this weight when the coils are stacked, these trays must, above everything else, be of strong and durable construction and capable of supporting many times their own weight. Consequently, the trays known prior to this invention have all taken the form of relatively thin doughnut-shaped rings having passageways extending from edge to edge and being closed on the upper and lower sides by imperforate metal plates. Even the strongest trays of this kind, however, will warp in use and will cause adjacent layers of coils engaged therewith to bear against each other with sufficient pressure to produce a weld, a very undesirable result.

It is accordingly a primary object of the present invention to provide a tray of novel design and construction which will assure much improved results in stack annealing by enabling the direct heating of the intermediate portions as well as the outer portions of coils by means of convection currents, and will be lighter but stronger than the trays heretofore known.

A further object of this invention is to provide an annealing tray which may take several different forms based on a common, novel pattern, to meet various requirements and purposes.

It is still another object of this invention to provide an annealing tray which may be reused many times, compared to previously known trays, under rigorous conditions without warping and causing portions of coils carried thereby to weld together in annealing, and without requiring maintenance or repair attentions.

An additional object of this invention is to provide an annealing tray which can be made of a minimum number of parts of relatively simple form, the assembly of which can be carried out easily and quickly without requiring special highly skilled labor.

A still further object of my invention is to pro-

2

vide an annealing tray of such form and design that the rate of gas flow through the tray can be fixed at any desired level in the operating range by varying the height or thickness of the tray, as by stacking trays atop of each other.

Further objects and important advantages of the present invention will become apparent to those skilled in the art upon consideration of the following detailed description thereof, reference being had to the drawings accompanying and forming a part of the specification, in which

Figure 1 is an elevational view partly in section of an annealing assembly, including trays embodying the present invention in several different forms;

Figure 2 is a fragmentary plan view of a tray of one form of this invention;

Figure 3 is a fragmentary plan view of another form of tray of this invention;

Figure 4 is a fragmentary horizontal sectional view of still another form of tray of this invention having a single connecting ring; and

Figure 5 is a fragmentary horizontal sectional view of a tray similar to that of Fig. 4, but having two rings.

As illustrated in these drawings, a tray of this invention is open transversely and, generally speaking, comprises a plurality of spaced apart curved ribs and a ring engaging said ribs and holding them together. Preferably these ribs are relatively thin and flat, disposed on-edge and curved longitudinally in the form of Archimedean curves. Also, these trays desirably have two rings concentrically related and engaging the inner and outer edge portions of the ribs, the inner rings refining axial openings in the trays. The ribs may, however, be of substantially square transverse cross section and may describe circle involutes or even corrugations (Fig. 3); and the rings may be located intermediately of the ribs, suitably extending through openings in said ribs.

The assembly shown in Fig. 1 includes a stack of coils C of strip stock with ring-like annealing trays T sandwiched between adjacent coils C, and a cup-shaped protective shell S enclosing the stack in a minimum space within a furnace. A centrifugal fan F or equivalent blower means is disposed below and coaxially with the stack to produce circulation of heated gas, suitably air, upwardly along the inner surface of shell S and into trays T, through coils C and downwardly through the open axial section of the stack, all as indicated by the several current-defining arrows. A cap piece P of ring shape is provided, having an axial opening of reduced diameter to

promote air flow over the top of the stack for uniform heating and annealing results. Lip 10 of the shell bears upon a supporting surface, i. e. the floor of the furnace, and is closed against penetration of furnace gas into the shell by means of a sand seal 11 or a liquid seal, an annular dam 12 being formed in the said surface and surrounding lip 10. Heat transference between the atmospheres of the furnace and shell S therefore is effected through the medium of the shell walls. Means for driving the fan or blower device does not constitute a part of this invention and will not be described as it may take any desired conventional form, as those skilled in the art will understand.

The lowermost tray T, which is disposed between fan F and the first coil, and supported on ring-like fan housing 15, generally resembles the trays illustrated in Fig. 2, having concentric inner and outer rings 17 and 18 and curved ribs 19 welded at their ends to the rings. In this case the ribs and rings are of the same width and approximately the same thickness. The diameter of the outer ring, however, is sufficiently greater than the outside diameter of the coil above it that an annular opening 21 is defined between the two for the purposes described above. Likewise, the inner ring is of sufficiently small diameter that an annular opening 22 is defined between the inner surface of the coil and said inner ring.

The tray in the second position above the fan resembles the one just described but for the fact that its inner and outer rings 25 and 26, respectively, are substantially narrower than ribs 27 joining them and are of a diameter more closely approaching the outside and inside diameters of the coil between these two trays. Ring 25 defines with the coils above and below the tray a pair of annular openings 28, and ring 26 defines a similar pair of openings 29 with the adjacent, opposed, outer edges of coils C.

The tray next above differs from the one just described in that the inner and outer rings 31 and 32, respectively, are of slightly larger and smaller diameters, respectively, than rings 25 and 26. Furthermore, ribs 33 joining rings 31 and 32, are recessed at their inner and outer edges and the rings are disposed within these edges, being secured suitably by means of welds.

The uppermost tray differs from all those described above quite materially in that it has two inner and two outer rings 40 and 41, respectively, and these are disposed on the upper and lower surfaces, rather than around the edges of, ribs 42, which are of substantially square cross section. As a result, this tray is open at the ends of the ribs and rings 40 and 41 serve the dual purposes of holding the ribs in relative position and retaining the coils. Unlike the second and third trays, this top tray should have an internal diameter substantially less than the coils in which it is to be used and an outside diameter substantially greater than that of those said coils, in order to allow sufficient space for the rings.

The tray of Fig. 2 comprises an inner ring 50, an outer ring 51 concentric therewith and a plurality of substantially equally spaced, relatively thin on-edge ribs 52 which are secured at their ends to the rings as by means of welds. These ribs define circle involutes and consequently the radial passageways defined by the ribs are wider at the outer ends than at their inner ends, although the ribs are equally spaced. It is seen

therefore that this tray may be either of the first two described above, depending upon the relative width of the rings and ribs.

The tray of Fig. 3 similarly is made up of an inner ring 55 and an outer ring 56 concentric therewith and a plurality of ribs 57 which are spaced substantially equally and are secured at their inner and outer ends to the rings 55 and 56, respectively, by suitable means. Ribs 57 are also relatively thin and disposed on-edge to afford maximum free space through the tray, but, unlike ribs 52, are of corrugated form. Rings 55 and 56 may take the form of rings 18, 26 or 41, shown in Fig. 1. Rings of the type of elements 32 may also be used, providing the inner and outer edges of ribs 57 are appropriately recessed.

The tray of Fig. 4 comprises a ring 60 and a plurality of relatively thin, on-edge and substantially equally spaced ribs 61 defining circle involutes and having transverse openings in register to receive ring 60 which secures and maintains the ribs together. In this case the ribs are necessarily somewhat wider than the ring, which preferably takes the form of a rod. Each of ribs 61 is provided with four spacing lugs 62 so that when the ribs are assembled together the lugs upon adjacent ribs will engage each other and serve to maintain the ribs in predetermined spaced relation during use.

The tray of Fig. 5 closely resembles the tray just described, having a plurality of substantially equally spaced relatively thin, on-edge curved ribs 68 provided with spacing lugs 69 near their inner and outer edges, and having transverse openings to receive connecting means. This means, however, differs from that of the previous tray, comprising two concentric rings 70 substantially equally spaced apart from the ends of ribs 68 and each other, as illustrated. Substantial additional stability is thereby realized at the cost of a negligible amount of free space, rings 70 being of substantially the same cross-sectional shape and dimensions as ring 60.

Although I have described the present invention in several preferred forms, I do not wish to be limited to these forms as will be clear from the appended claims. It will be understood, for instance, that the ribs need not be of Archimedean curve form, but may describe circle involutes, circumferential tangents and the like, or may be of corrugated form, so long as they give substantially the advantages and results stated above. Also, the bar width may be varied from the proportions shown to meet various requirements and demands arising with different gas volumes and speeds and different types of annealing equipment.

Having thus described the present invention so that those skilled in the art may be able to understand and practice the same, I state that what I desire to secure by Letters Patent is defined in what is claimed.

What is claimed is:

1. A generally ring-shaped annealing tray to be disposed between and to engage two stacked coils of metal stock to be heated and annealed comprising a plurality of substantially uniformly spaced, longitudinally-curved, metal ribs co-operating to define a plurality of open-ended channels through which heating fluid may flow, and means including a metal ring engaging and securing said ribs together, said metal ribs having spaced inner and outer ends and having edge portions exposed for the entire length of the

ribs and cooperating with each other to define a side of the tray for engagement with a coil to be annealed, and said ring being spaced from the coil-engaging side of the tray between the inner and the outer extremities of the ribs.

2. A generally ring-shaped annealing tray to be disposed between and to engage two stacked coils of metal stock to be heated and annealed comprising a plurality of substantially uniformly spaced, longitudinally-curved, metal ribs cooperating to define a plurality of open-ended channels through which heating fluid may flow, and means including metal concentric rings circumferentially securing said ribs together at their inner and outer extremities, said rings each being of thickness substantially less than one-half the thickness of the tray, and said metal ribs having spaced inner and outer ends defining inner and outer peripheries of the tray and having edge portions exposed for substantially the entire length of the ribs and cooperating with each other to define one side of the tray for engagement with a coil to be annealed.

3. A generally ring-shaped annealing tray to be disposed between and to engage two stacked coils of metal stock to be heated and annealed comprising a plurality of substantially uniformly spaced, longitudinally-curved, metal ribs cooperating to define a plurality of open-ended channels through which heating fluid may flow, and means including concentric metal rings circumferentially engaging and securing said ribs together at their inner and outer extremities, said metal ribs having spaced inner and outer ends and having edge portions exposed for the entire length of the ribs and cooperating with each other to define top and bottom sides of the tray for engagement with coils to be annealed.

4. A generally ring-shaped annealing tray to be disposed between and to engage two stacked coils of metal stock to be heated and annealed comprising a plurality of substantially uniformly spaced, longitudinally-curved, metal ribs cooperating to define a plurality of open-ended channels through which heating fluid may flow, and means including a pair of metal rings engaging and securing said ribs together at their outer extremities and another pair of metal rings concentric with the first ring pair and engaging and securing said rings together at their inner extremities, said metal ribs having spaced inner and outer ends and having edge portions exposed for the entire length of the ribs and cooperating with each other to define top and bottom sides of the tray for engagement with coils to be annealed, and said rings being disposed on said top and bottom sides of the tray.

5. A generally ring-shaped annealing tray to

be disposed between and to engage two stacked coils of metal stock to be heated and annealed comprising a plurality of substantially uniformly spaced, longitudinally-curved, metal ribs cooperating to define a plurality of open-ended channels through which heating fluid may flow, and means including concentric metal rings circumferentially securing said ribs together, said metal ribs having spaced inner and outer ends and having edge portions exposed for the entire length of the ribs and cooperating with each other to define top and bottom sides of the tray for engagement with coils to be annealed, and said rings being of thickness substantially less than one-half the thickness of the tray and engaging the inner and outer extremities of the ribs between said top and bottom sides of the tray.

6. A generally ring-shaped annealing tray to be disposed between and to engage two stacked coils of metal stock to be heated and annealed comprising a plurality of substantially uniformly spaced, longitudinally-curved, metal ribs cooperating to define a plurality of open-ended channels through which heating fluid may flow, and means including concentric metal rings circumferentially securing said ribs together, said metal ribs having spaced inner and outer ends and having edge portions exposed for the entire length of the ribs and cooperating with each other to define top and bottom sides of the tray for engagement with coils to be annealed, and said rings being of thickness substantially the same as the thickness of the tray and engaging the inner and the outer extremities of the ribs.
